United States Patent Office.

FREDERICK VETTERLIN, OF NEUHAUSEN, SWITZERLAND.

Letters Patent No. 109,277, dated November 15, 1870; antedated November 11, 1870.

IMPROVEMENT IN BREECH-LOADING FIRE-ARMS.

The Schedule referred to in these Letters Patent and making part of the same.

To all whom it may concern:

Be it known that I, FREDERICK VETTERLIN, of Neuhausen, in the Canton of Schaffhausen, Switzerland, have invented certain new and useful Improvements in Breech-loading Fire-Arms; and I do hereby declare that the following is a full, clear, and exact description of the same, reference being had to the accompanying drawings making a portion of this specification, in which—

Figure 1 is a central longitudinal section of a fire-arm made according to my invention.

Figure 2 is a plan view the same.

Figure 3 is a partial longitudinal section of the breech-closing mechanism.

Figure 4 is a transverse section of the same, taken in the line $x x$ of fig. 1.

Figure 5 is a transverse section, taken in the line $y y$ of fig. 1.

Similar letters of reference indicate corresponding parts in all the figures.

This invention consists in the arrangement of an extractor, formed with an elastic extension, within a groove provided in the upper side of the breech-piece, and in such relation with a suitable covering-plate as not only to secure the retention of the extractor in its place, but, furthermore, to insure the most effective operation of such extractor in withdrawing the cartridge-shell from the barrel.

To enable others to understand the construction and operation of my invention, I will proceed to describe it, with reference to the drawings.

The breech-receiver A has the barrel B screwed into its forward end, and is secured in any suitable manner to the stock C.

The interior of this breech-receiver is of circular or cylindrical form, and has an opening, A*, provided in the upper side of its forward portion, through which the cartridge is introduced preparatory to being forced forward to its place in the barrel, as hereinbefore fully explained.

The breech-receiver is open at its rear end, to permit the extension therethrough of certain parts, hereinafter presently described, of the breech-closing mechanism, and adjacent to such rear end is chambered or enlarged, as shown at B*, there being in rear of such enlargement any desired number, but preferably three, of lugs, a, the forward end surfaces of which are situated in planes at right angles to the axis of the barrel and breech-receiver, and constitute the recoil-bearings of the breech-piece C.

This breech-piece C is of cylindrical form to fit the breech-receiver, and has its rearmost portion reduced in size behind the shoulders b, in order to permit a sleeve or collar, D, to be fitted thereon, the collar being loosely screwed at its rear end upon the corres-

ponding end of the breech-piece, in such manner as to be retained in place thereon, and at the same time be capable of being turned around upon the same.

Firmly secured upon the rear portion of the collar D is a laterally-extending lever, E, by means of which the turning movement just mentioned is effected.

The collar D is, furthermore, provided at its forward end with radial ears, e, the rear surfaces of which are square with the axis of the breech-piece, so that, when the latter is pushed forward to close the breech, and the lever E is turned downward to bring the ears e immediately in front of the lugs a, the breech-piece will be locked in place and supported against any force, as, for instance, that of the explosion in firing, exerted to drive it or move it back, while, by turning the lever upward, to bring ears e opposite to or in line with the spaces between the lugs a, the breech-piece may be drawn back to unclose the breech, the ears passing through the spaces just indicated in such backward movement of the breech-piece.

The firing-pin, shown at G, is fitted into an axial bore formed within and extending the whole length of the breech-piece, the rearmost end of the firing-pin being made of rectangular or equivalent form in its cross-section, and fitting through a hole or slot, of corresponding form, provided in a cap, C*, screwed upon the rearmost end of the collar D, in such manner that the turning movement of the collar in either direction will be imparted to the pin, without interference with the longitudinal movement requisite to the latter.

The firing-pin is furthermore provided with a lateral spur, f, the forward surface of which is inclined, and the adjacent side of the rear end of the breech-piece is notched in such manner that an inclined plane, g, is formed thereon, the arrangement being such that, when the collar D, together with the firing-pin, are turned preparatory to the backward movement of the breech-block, as just hereinbefore explained, the inclined surface of the spur f being acted upon by the inclined plane g on the breech-piece, the firing-pin is forced back until the forward end thereof is brought inward beyond the face of the breech-piece, and the spur f is brought past the rear extremity of the breech-piece in such manner as to prevent the firing-pin from moving forward in case the hammer H should, from any cause, descend upon the same when the collar is thus turned to unlock the breech-piece.

When the collar is brought to its first position to lock the breech-piece in its place the notch or inclined plane g is, of course, brought in such relation with the spur f as to permit the forward movement of the firing-pin to ignite the charge when acted upon by the hammer.

Provided in the upper side of the breech-piece is a

longitudinal groove, *m*, the forward portion of which is made deeper than the rest, in order to receive the extractor I.

The forward end of the extractor constitutes a hook, *n*, projecting beyond the face of the breech-piece, and the office of which is to catch upon the flanch or rim of the cartridge-shell, to extract the latter when the breech is opened.

Extending back from the rear end of the extractor is a spring or elastic extension, *r*; and secured by suitable screws in the more shallow portion of the groove *m*, and projecting forward over the extension just mentioned is a plate, *s*, which serves to hold the extractor in its place.

This plate *s* is furthermore provided with a shoulder, *u*, which, by striking at the rear end of the opening A* when the breech-piece is drawn back, limits the extent of such movement.

When the breech-piece is pushed to close the breech the elastic extension *r* allows the hook of the extractor to pass over and catch upon the flanch of the cartridge-shell, so that, when the breech-piece is drawn back in opening the breech, the shell will be pulled back therewith until, striking against a fixed stud, *u*, provided in the bottom of the breech-receiver, it is

tilted upward and thrown out from the latter, whereupon a cartridge being dropped into the receiver in front of the breech-piece, the forward movement of such piece drives the cartridge to its place in the barrel; and the breech-piece being locked by the turning movement of its collar, as hereinbefore explained, the loading of the arm is complete, it being only necessary to pull the trigger in order to fire the arm, the hammer having been brought to the position of full-cock by the backward movement of the breech-piece in opening the breech.

What I claim as my invention, and desire to secure by Letters Patent, is—

The arrangement of the extractor I, formed with an elastic extension, *r*, within a groove in the upper side of the breech-piece, and in relation with the covering-plate *s*, whereby not only is the extractor retained in place, but the most efficient action of such extractor in the withdrawal of the cartridge-shell is secured, substantially as herein set forth.

FREDERICK VETTERLIN.
